US00D975164S

(12) **United States Design Patent** (10) **Patent No.:** **US D975,164 S**
(45) **Date of Patent:** **** Jan. 10, 2023**

(54) **WEBCAM DEVICE**

(71) Applicant: **Acer Incorporated**, New Taipei (TW)

(72) Inventors: **Yun Cheng**, New Taipei (TW);
Tsun-Chih Yang, New Taipei (TW)

(73) Assignee: **Acer Incorporated**, New Taipei (TW)

(**) Term: **15 Years**

(21) Appl. No.: **29/785,035**

(22) Filed: **May 24, 2021**

(30) **Foreign Application Priority Data**

Jan. 19, 2021 (TW) 110300318

(51) **LOC (14) Cl.** **16-01**

(52) **U.S. Cl.**

USPC **D16/211; D16/214**

(58) **Field of Classification Search**

USPC D16/200, 202–204, 208, 211, 214, 218,

D16/219, 243; D10/57, 70

CPC G03B 17/00; G03B 17/02; G03B 2217/00;

H04N 5/225

(57) **CLAIM**

The ornamental design for a webcam device, as shown and described.

DESCRIPTION

FIG. 1 is a perspective view of a webcam device showing our new design;

FIG. 2 is another perspective view thereof;

FIG. 3 is another perspective view thereof;

FIG. 4 is another perspective view thereof;

FIG. 5 is another perspective view thereof;

FIG. 6 is a front view thereof;

FIG. 7 is a rear view thereof;

FIG. 8 is a left side view thereof;

FIG. 9 is a right side view thereof;

FIG. 10 is a top view thereof;

FIG. 11 is a bottom view thereof;

FIG. 12 is a perspective view thereof showing the webcam device in another usage state;

FIG. 13 is another perspective view thereof showing the webcam device in another usage state;

FIG. 14 is a perspective view thereof showing the webcam device in the storage state;

FIG. 15 is another perspective view thereof showing the webcam device in the storage state;

FIG. 16 is a perspective view thereof showing the webcam device detached from the base; and,

FIG. 17 is another perspective view thereof showing the webcam device detached from the base.

The broken lines illustrate portions of the webcam device that form no part of the claimed design. The oblique line shading shown in the drawings indicates a transparent or translucent surface.

1 Claim, 14 Drawing Sheets
